Primary Examiner — Messina L Smith*Assistant Examiner* — Noah Perez(74) *Attorney, Agent, or Firm* — Johnston IP Law, PLLC(57) **CLAIM**

The ornamental design for a controller housing, as shown and described.

DESCRIPTION

FIG. 1 is a front perspective view of a controller housing showing our new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

The broken lines in the Figures show portions of the controller housing that form no part of the claimed design.

1 Claim, 5 Drawing Sheets(56)
